UNITED STATES PATENT OFFICE

99,970

DESIGN FOR A DETACHABLE BATHTUB SEAT

Mae Winch, San Francisco, Calif.

Application March 24, 1936, Serial No. 61,756

Term of patent 14 years

To all whom it may concern:

Be it known that I, Mae Winch, a citizen of the United States of America, residing at San Francisco, in the county of San Francisco and State of California, have invented a new, original, and ornamental Design for a Detachable Bathtub Seat, of which the following is a specification, reference being had to the accompanying drawing, forming a part thereof.

The figure is a perspective view of the article, showing my new design.

I claim:

The ornamental design for a detachable bathtub seat substantially as shown.

MAE WINCH.
